CIGAR LIGHTER

Ferdinand Ringer, Vienna, Austria

Application November 29, 1937, Serial No. 177,096
In Austria December 1, 1936

7 Claims. (Cl. 67—7.1)

My invention relates to cigar lighters comprising a body of solid fuel adapted to be ignited by a spark producing igniting device. For the use of such fuel bodies cigar lighters are suitable in which the face of the fuel body before being ignited is roughened or loosened, this action being hereinafter referred to as roughening. In order that the roughening tool may properly operate, the fuel body must be pressed against 10 or moved to contact with the roughening device prior to the actuation of the roughening device, whereas the fuel body must be held in position on being ignited. It has already been proposed, to so construct the roughening device of cigar 15 lighters using said devices, that it serves itself as a stop for the fuel body which is constantly pressed against the roughening device, or to provide a separate stop or a grid serving as a stop for the fuel body which latter is roughened transverse across the opening of the grid. These known arrangements are open to the objection that the face of the fuel body is partly covered when ignition is intended to be effected which not only interferes with a reliable ignition but 20 also results in an irregular burning off of the fuel body. Besides that the incomplete combustion due to the permanent contact with metal parts results in the formation of residues and undesirable by-products. Moreover the metal parts undergo changes in texture and are deformed or even destroyed under the action of the heat of the flame.

For avoiding the deficiencies just referred to, according to the present invention a clamping 35 device is provided which automatically firmly engages the fuel body in its guide at a point remote from the face to be roughened in a manner known per se, at least at the moment of making the cigar lighter ready for use (say 40 by opening the cover or pulling out the rubbing pin), while on putting the cigar lighter out of use (say by closing the cover or pushing in the rubbing pin respectively) the fuel body is automatically disengaged for permitting the same to be fed. The use of such clamping devices has already been proposed for cigar lighters with igniting sticks adapted to be repeatedly ignited by rubbing. In such cigar lighters, however, on the one hand no roughening devices are used and 45 on the other hand the problems connected with the extraneous ignition do not occur at all. More particularly the requirement met with in the case of extraneous ignition of an unimpeded access of the stream of sparks to the roughened 50 face of the fuel body and the avoiding of losses

in heat by cooling do not play any part in the case of cigar lighters of the type last referred to.

The annexed set of drawings illustrates by way of example several construction forms of a cigar lighter embodying the present invention. 5

Fig. 1 shows a side view of a constructional form of the cigar lighter according to the invention, the parts of the construction enclosed by the lighter box being indicated by dotted lines;

Figs. 2 and 3 show other modifications of the 10 lighter in cross section;

Figs. 4 and 5 are representing further modifications of the lighter according to Fig. 1. Finally,

Fig. 6 shows a rubbing cigar lighter constructed according to the present invention modifying the construction of Fig. 1. 15

In the constructional form illustrated in Fig. 1, 1 is the casing and 2 is the cover of the cigar lighter. 4 is a control bar suitably guided and forced against a stop 3 by a spring 5 abutting 20 against the bottom of the casing. In the cover the usual rubbing wheel 6 is mounted against which a spark producing rod say consisting of an alloy of cerium and iron is elastically forced and guided in a suitable sleeve 7, so that on opening the cover in the usual well known manner the rubbing wheel 6 is rotated by means of a suitable mechanism not shown and a stream of sparks is produced. 25

The rod-like shaped fuel body 8 consisting of 30 combustible fibres and an agglomerant likewise combustible, in which said fibres are embedded, is guided in a sleeve 9 having a slot at its upper end and being conical at its outer side, so that a clamping ring 10 slidably mounted on the conical part of the sleeve 9 and acted upon by a spring 21 abutting against the bottom of the casing may cause the fuel body 8 to be clamped 35 in the sleeve 9.

A lever 12 is pivoted at 11 in the casing and carries at one end an arm projecting from the body of said lever at substantially right angles. This arm carries on one side points, teeth 13 or similar elements adapted to loosen or roughen. A pusher 15 provided with a longitudinal slot 16 is pivoted at 14 to the lever 12. Into the slot 16 engages a pin 17 fast on the casing or on a part secured to the casing. A spring 18 secured to the casing permanently tends to turn the lever 12 in an anticlockwise direction so that the free end of the pusher 15 is pressed against an incline 19 provided on the member 4. 40

In the position of the parts of the cigar lighter as shown in Fig. 1 the cover 2 is closed and the lever 12 is in its extreme left hand position in 45

which the device 13 is above the fuel body 8. The pusher 15 bears against the bottom end of the incline 19 and the clamping ring 10 is then in its lowermost position, in which it is retained by a stop 15' on the pusher 15, which hooks over the clamping ring 10, or by the cover 2 and liberates the sleeve 9 to such an extent that its parts can elastically recede from each other thus liberating the fuel body which is forced against the device 13 by the spring 20.

If now the cover 2 is opened it pushes downward the control element 4 compressing the spring 5, and the pusher 15 is shifted to the right by the incline 19 turning the lever 12 in the clockwise direction against the action of the spring 18, whereby the teeth 13 loosen or roughen the face of the fuel body, while at the same time the clamping ring 10 is disengaged from the stop 15' of the cover or the pusher and is pushed upwards by the spring 21, so that the end of the sleeve 9 is contracted and the fuel body is firmly clamped. More particularly, the pusher 15 by its travel towards the right raises the lever 12, which is pivoted at 11, and thereby is caused to pivot around pin 17. The right side of the pusher 15 is raised consequently and the stop 15' travels upwardly for a corresponding distance. This permits the clamping ring 10 to travel upwardly by reason of the action of spring 21 until it engages the conical upper end of sleeve 9. The opening of the cover resulted simultaneously in producing the sparks in the usual manner which sparks on hitting the loosened or roughened face of the fuel body ignite the latter. By closing the cover 35 the flame is extinguished and the parts are returned into the position shown in Fig. 1.

The disengagement of the clamping ring 10 can also be effected manually by means of moving a knob connected with the clamping ring and extending to the outside of the lighter through a slot in the casing 1. Such an arrangement is not shown in Fig. 1, but illustrated in Fig. 5, where knob 51 is shown to extend to the outside of the casing, the knob can be shifted manually while the cover 2 is open. The insertion of a replacement fuel body 8 is facilitated by such arrangement.

It will be understood that by repeated actuation of the device 13 the face of the fuel body exposed to the stream of sparks will be roughened and thereby an incline is formed on the fuel body which corresponds to the path of the teeth 13 oscillating around the pivot point 11. This path is situated within the stream of sparks bringing about the ignition and thus a proper ignition is secured.

In the constructional form illustrated by Fig. 2 the roughening device 13 is mounted on an arm 22, pivoted at 23 on the cover 2. A spring 24 forces the arm 22 carrying the device 13 against the fuel body 8. Furthermore an arm 25 which is pivoted in the cover at 26, remains, while the cover is in closed position, in engagement with an arm 27 of a lever 29 pivoted at 28 in the casing. A solid or hollow metallic block 2' abuts on arm 25 and acts as a stop for it. The free end of lever 29 is connected with the clamping ring 10 so that on closing the cover the ring 10 is pushed downwards against the action of the spring 21, thus liberating the fuel body in the slotted end of the sleeve, whereas on opening the cover the lever 27, 29 is freed and the spring 21 causes the fuel body to be clamped in position in the same manner as above described with reference to Fig. 1. 75 On opening the cover the device 13 is pulled

across the face of the fuel body, thus loosening or roughening this face. The locking device of the cover and the arrangement of the latter, as also the arrangement of the igniting device comprising a rod of an alloy of cerium and iron are substantially the same in construction as in the cigar lighters heretofore constructed.

In the constructional form illustrated in Fig. 3 there is also provided an arm 22' mounted in the cover and carrying the roughening device 13, said arm carrying at its free end a guiding roller 30 moving along a guide element 31 secured in the casing. A spring 24' attached on the one hand to the cover 2 and on the other hand to the arm 22' tends to pull the free end of the arm 22' with its guiding roller 30 against the guide element 31. This guide element is so shaped that when the cover is closed the device 13 is above the fuel body 8. In the casing there is furthermore an arm 33 pivoted at 32 and connected to the clamping ring 10. On closing the cover 2 the arm 33 is swung downwards by the arm 22', when the latter reaches the bottom side of the guide element 31, whereby the clamping ring 10 is moved downward and the fuel body 8 is liberated in the same manner as described with reference to Fig. 1 and 2, so that the spring 20 is allowed to press the said body against the device 13. The parts 22', 13, 31, 33 are arranged laterally of the fuel body, for instance in a place situated between the fuel body 8 and a side wall of the casing 1. The spring actuated arm 49 tends to hold the cover 2 in its open position. Otherwise the operation of this cigar lighter is the same as that described with reference to Figs. 1 and 2.

In the constructional form illustrated in Fig. 4 the sleeve 9 carrying the fuel body is arranged to be rotatable around its geometrical axis. A disc 34 is rigidly connected with the sleeve 9 said disc projecting through a slot 35 in the wall of the casing.

The projection 36 serving for locking the cover 2 is carried by one arm of a two armed lever 37, pivoted in the casing at 38. A spring indicated at 40 tends to hold the lever 37 in that position in which the locking hook 39 carried by the cover 2 and capable of receding resiliently strikes against the projection 36 on closing the cover. The disc 34 carries a pin 41 which on turning the disc 34 strikes against the end of the lever 37, turning the latter around its pivot pin 38, so that the projection is turned out of the path of the locking hook 39.

The roughening device 13 is contained in the cover of the cigar lighter and is above the fuel body 8 as long as the cover 2 is closed. If with the cover being still closed the disc 34 is turned, then corresponding to the turning movement of the sleeve 9 up to the striking of the pin 41 on the end of the lever 37 a roughening of the face of the fuel body 8 is brought about by the device 13. On continuing the rotating of the disc 34 the lever 37 will be turned and thereby the projection 36 is disengaged from the hook 39 and the cover is automatically opened by the usual cover spring and at the same time the production of sparks and the ignition is effected in the usual manner. Before closing the cover the projection 36 must be turned back into the locking position by turning the disc 34 in the opposite direction or this turning back may be brought about automatically by a spring.

The feed of the fuel body is effected when the cover 2 is closed, by means of a bracket (not shown) on the cover 2, which on closing the cover

strikes against the clamping ring 10 and pushes it downward against the action of the spring 21.

In the constructional form illustrated in Fig. 5 the rotation of the sleeve 9 enclosing the fuel body 8 is brought about by an arm 50 secured to said sleeve and passing through a slot in the casing. The arm 50 carries a knob 51 at its free end. The sleeve 9 or a ring fixed thereto carries the projection 36 which engages the locking hook 10 39 so that on turning the sleeve 9 the cover 2 is unlocked and the projection 36 on being turned retains its distance from the neighbouring vertical wall of the casing. In all other respects the operation of this constructional form of the cigar lighter is the same as that of the constructional form illustrated in Fig. 4.

The constructional form illustrated in Fig. 6 has for its object the application of the present invention to a rubbing cigar lighter. The casing 20 1 of a rubbing cigar lighter comprises a chamber 41' at the bottom of which the roughening device 13 is mounted, preferably yieldingly. On the outside of the casing is provided a rubbing surface 42. In the chamber 41' the carrier of the bar 25 shaped fuel body 8 is mounted. This carrier consists of a sleeve 9 directly enclosing the fuel body 8 and slotted in its upper part. This sleeve 9 encloses a spring 20 serving for feeding the fuel body 8. On the sleeve 9 is slidably mounted a 30 clamping ring or sleeve 43 onto which is screwed the hollow head 44 projecting from the casing 1 when the carrier is inserted into the chamber 41'. The free end of the sleeve 43 is conical in shape and carries a rod 45 of an alloy of cerium and 35 iron serving for producing sparks at the rubbing surface 42. A spring 21 interposed between the bottom of the sleeve 9 and the head 44 forces the end of the sleeve 9 against the conical part of the sleeve 43, whereby the fuel body 8 is firmly 40 clamped. Furthermore the sleeve 9 carries a pin 46 projecting through a hole in the sleeve 43 or the head 44 and being introduced into a slot 47 in the wall of the casing 1 when the carrier is inserted into the chamber 41', said slot comprising 45 two parts at right angles to each other.

On inserting the carrier of the fuel body 8 into the chamber 41' the pin 46 enters into that part of the slot 47, which is parallel to the direction of insertion, and slides along the slot 47 until it abuts 50 against the edge of the slot. Now the pin 46 prevents the sleeve 9 from continuing its rectilinear movement, so that then it is only the sleeve 43 that continues its movement, the spring 21 being compressed thereby liberating the fuel body 55 8 and allowing it to be fed. When the pressure on the carrier directed to the inside of the casing ceases, the spring 21 causes the sleeve 43 to move backwards and the fuel body 8 to be clamped again. The carrier is prevented from falling out 60 of the chamber 41' by balls 48, connected with springs (not shown) secured to the wall of the chamber 41', which springs force said balls into recesses on the outside of the sleeve 43. If now in this position of the parts the sleeve 43 is turned 65 the pin 46 enters the second part of the slot 47 which is at right angles to the first part whereby the carrier is locked in its position and at the same time by said turning the face of the fuel body 8 is roughened by the device 13.

70 If the carrier is turned in the reverse direction, so that the pin 46 reenters the part of the slot 47 parallel to the direction of insertion, the carrier can be pulled out of the chamber 41', the resistance of the spring actuated balls 48 being 75 overcome, whereupon by rubbing the cerium-iron

rod 45 on the rubbing surface 42 the sparks igniting the fuel body 8 are produced.

It will be understood that in detail the construction of the cigar lighter showing the essential features of the present invention may be 5 varied in many directions without departing from the essence of the invention. Thus for instance the oscillating movement required for ignition may be imparted to the fuel body while the roughening device is stationary, or a rotary movement around its own axis may be imparted to the roughening element while the fuel body is held in its position. Finally the roughening device and the fuel body may be moved simultaneously in 10 opposite directions for roughening the fuel body. 15

The invention is particularly useful for solid fuels containing combustible fibres which must be laid free prior to each ignition by roughening or loosening.

What I claim is:

1. A cigar lighter comprising a housing, a cover on said housing, a solid fuel body, a guide member adapted to enclose said fuel body, roughening means acting against the face of said fuel body, spark producing means coming into operation 20 after the action of said roughening means, clamping means adapted to hold firmly said fuel body in said guide at a point below the face to be roughened, a feed spring for said fuel body controlling by said clamping device, means for engaging and disengaging said controlling device, and connecting means between said controlling means and said cover. 20

2. A cigar lighter as claimed in claim 1, in which the cover of the casing of the cigar lighter 35 is adapted, on moving for opening and closing said casing, to impart an oscillating movement to the said roughening device, and interconnecting means between the cover and the clamping device serving to bring about the opening and closing of the clamping device in immediate dependency of the movement of the cover. 40

3. A cigar lighter as claimed in claim 1, in which the cover of the casing of the cigar lighter is adapted, on moving for opening and closing 45 said casing, to impart an oscillating movement to the said roughening device, and interconnecting means between the cover and the clamping device serving to bring about the opening and closing of the clamping device in immediate dependency of the movement of the cover, the cover being adapted to actuate a movable control element which is under the action of a spring and provided with a camlike part which control element acts on an intermediate member such as 50 a pusher operatively connected with the roughening device capable of making an oscillating movement and with the clamping device for the fuel body. 55

4. A cigar lighter as claimed in claim 1, in 60 which the fuel rod and the roughening device are positioned so as to bring about the roughening of the fuel rod by the rotary movement of the said rod relative to the roughening device around the geometrical axis of said fuel rod, and an interconnection between the means controlling the said rotary movement on the one hand and the cover on the other hand, adapted to control the opening of the cover of the cigar lighter, the movement of the igniting device and the closing movement of the clamping device of the fuel rod being in dependency of the rotation of said fuel rod. 65

5. A cigar lighter as claimed in claim 1, in which the fuel rod and the roughening device are positioned so as to bring about the roughening 70 75

of the fuel rod by the rotary movement of the said rod relative to the roughening device around the geometrical axis of said fuel rod, and an interconnection between the means controlling the said rotary movement on the one hand, and the cover on the other hand, adapted to control the opening of the cover of the cigar lighter, the movement of the igniting device and the closing movement of the clamping device of the fuel rod being in dependency of the rotation of said fuel rod, said rotating means comprising a support of said fuel rod and an arm in engagement with said support and said cover, whereby said support is rotated by the closing and opening of said cover.

15 6. A cigar lighter as claimed in claim 1, designed for rubbing manipulation further characterised by the fact that the clamping device of the fuel body is operatively connected with an element controlling the movements of the fuel rod and its guide, in a manner ascertaining that on inserting the carrier of the fuel body into the casing of the cigar lighter the clamping device of

the fuel body is released and the spring actuated fuel body is forced against the roughening device enclosed in the casing.

7. A cigar lighter as claimed in claim 1, designed for rubbing manipulation further characterised by the fact that the clamping device of the fuel body is operatively connected with an element controlling the movements of the fuel rod and its guide, in a manner ascertaining that on inserting the carrier of the fuel body into the casing of the cigar lighter the clamping device of the fuel body is released and the spring actuated fuel body is forced against the roughening device enclosed in the casing, further characterised by the fact that between the fuel carrier and the casing an interconnection is provided so as to bring about a rotary movement of the fuel body relatively to the roughening device through the locking movement in the clamping position of the fuel carrier introduced into the casing.
